UNITED STATES PATENT OFFICE.

WILLIAM MARCROFT, OF CRANSTON, RHODE ISLAND, ASSIGNOR TO UNIVERSAL WINDING COMPANY, OF PORTLAND, MAINE, A CORPORATION OF MAINE.

BUNCH-BUILDING ATTACHMENT FOR WINDING-MACHINES.

1,084,459.

Specification of Letters Patent. Patented Jan. 13, 1914.

Application filed May 22, 1913. Serial No. 769,294.

To all whom it may concern:

Be it known that I, WILLIAM MARCROFT, a citizen of the United States, residing at Cranston, in the county of Providence, and State of Rhode Island, have invented certain new and useful Improvements in Bunch-Building Attachments for Winding-Machines, of which the following is a specification:

10 My invention relates to improvements in winding machines for winding weft or filling into cops or bobbins for use in the shuttles of looms.

15 My improvement consists particularly in providing means for automatically controlling the traverse of the thread or yarn at the beginning of the winding in such manner that a preliminary winding or "bunch" is first laid on the yarn-receiver or naked bobbin before the main or "service" winding is built up with the full traverse. The relatively short length of yarn in the primary winding or "bunch" is designed to prevent the bobbin from being entirely exhausted before the "feeler-devices" of the loom can operate to replenish the shuttle. In automatic "feeler-looms" the "feeler" acts to cause a change of filling when the yarn has been woven off the bobbin down to the preliminary winding, the bunch still containing sufficient yarn to last while the change is being made. The extra yarn in the bunch insures against loose ends or "miss-picks" in the cloth should the filling in the main portion of the bobbin run out while the shuttle is crossing from one side of the loom to the other and back again.

20 The principal object of my invention is to provide a device which can be applied to winding machines already in use without requiring a change in the traverse-mechanism thereof. With this object in view I have devised a mechanism which is adapted to control the laying of the yarn at the beginning of the winding independently of the operation of the traverse-guide.

25 My new device acts to hold the yarn from being traversed by the guide during the first few reciprocations of the latter and is then automatically operated to release the yarn to permit of its being traversed in the usual way.

30 The invention also provides for adjustment of the holding-means for the yarn to regulate the position of the bunch in rela-

tion to the butt of the bobbin; and further, the mechanism can be set to give any desired number of coils or turns in the bunch-winding according to the length of extra yarn required for different widths of cloth. 60

My new device serves as a complete, self-contained mechanism which can be applied to any usual type of winding machine by attaching it to the frame thereof without any change whatsoever in the mechanism of 65 the machine.

The invention is fully described in the following specification, illustrated by the accompanying drawings, in which like letters of reference designate like parts. 70

In the drawings: Figure 1 is a plan view of a portion of a well known type of winding machine illustrating the essential elements thereof consisting of the winding-spindle, traverse-bar and thread-guide, and showing my new bunch-building device as applied thereto; Fig. 2 is an enlarged, plan view of the new device shown detached from the machine and illustrating the position of the yarn-controlling arm at the beginning of the winding, when the bunch is being wound; Fig. 3 is a similar view showing the position of the arm after its release when the bunch-winding is completed; Fig. 4 is a side elevation of the device with the cover shown in section to reveal the parts inclosed thereby; Fig. 5 is an end view with the cover also shown in section; Fig. 6 is a detail view of the ratchet and pawl mechanism for operating the device; Fig. 7 is a part-sectional view of the same taken on the line A—A of Fig. 6, looking in the direction indicated by the arrow a; Fig. 8 is a plan view of the yarn-controlling arm shown as being adapted for adjustment in length; 95 Fig. 9 is a detail view of the stud on which the controller-arm is mounted.

Referring first to Fig. 1 my invention is here shown as applied to a machine of the same general type as that described in U. S. 100 Patents No. 940,489 and No. 946,831, granted Nov. 16, 1909 and Jan. 18, 1910 respectively to S. W. Wardwell. It will be obvious, however, that my new device might be adapted to any other style of machine employing a rotating spindle and reciprocating guide or to machines in which the spindle is reciprocated instead of the guide to effect the traverse of the yarn. As here illustrated the basic machine consists essentially of a 110

rotating winding-spindle B and a reciprocating traverse-bar C, the latter arranged opposite the spindle and adapted to carry the yarn- or traverse-guide G which is provided with a yarn-guiding groove G'. Besides its movement with the bar C the guide G is also fed progressively outward thereon to adapt it to lay the yarn in superimposed, conical layers advancing along the spindle to build the cop or bobbin by longitudinal extension of the yarn mass. The winding-spindle B is mounted to rotate in bearings in the main frame D of the machine and is driven through suitable instrumentalities not here shown or described. A portion of the spindle B overhangs the front of the frame and is adapted to receive the yarn-holder or wooden-bobbin b. In some cases a paper tube is used on the spindle B in place of the wooden bobbin b here shown, or any other form of yarn-receiver might be employed.

The traverse-bar C is adapted to reciprocate in bearings in the frame D and is actuated from a rocker-arm or other suitable mechanism not here shown or described. The bar C is preferably constructed in two parts C' and C² which are connected at their adjacent ends by a pin-and-slot arrangement shown at c. The outer end of the extension C² is mounted in a swiveled, outboard bearing c' which allows the inner end to swing inward toward the winding-spindle B. The thread-guide G is supported at the end of an arm or guide-holder g which is hinged on the bar C². Mounted on the bar C² between the two legs of the thread-guide-holder g is a nut g' engaging the screw-threads c² to feed the guide along the bar. A contact-wheel g² carried on the nut g' is adapted to engage the winding and is turned thereby through the rotation of the winding-spindle to advance the guide with respect to the bobbin. The swiveled arrangement of the bar C² allows the wheel g² to be pressed in toward the winding-spindle B to adapt it to engage the first layers of yarn wound on the bare bobbin and these elements operate in connection with a former-arm g³ shown and described more particularly in Patent No. 946,831 to S. W. Wardwell, before mentioned.

My new device is practically independent of the above described mechanism, but is arranged in relation thereto as now explained: Briefly it consists of a controller-arm E having its outer end formed with a curved opening e to receive the yarn y and adapted to be maintained in the position illustrated by full lines in Fig. 1 at the commencement of the winding to hold the yarn from being traversed on the bobbin by the guide G. After the bunch-winding is completed the arm E is automatically thrown into the position illustrated by the dotted lines in Fig.

1 to release the yarn from the opening e and allow the guide G to traverse it on the bobbin. The mechanism for operating the arm E is contained in a small box or casing F which is secured to the frame D. The operating parts of the mechanism derive their motion from the reciprocating traverse-bar C and are arranged as now described.

The casing F consists simply of a flat plate f formed with two upturned ends f', f'. The plate f is secured to the top of the frame D by a screw f² extending through a slot f³. A lug f⁴ extending downwardly from the plate f at one end thereof abuts the front edge of the frame D and with an adjusting screw f⁵ at the opposite end serves to locate the plate with respect to the traverse-mechanism of the machine, see Figs. 1 and 5. The screw f⁵ extends through a lug f⁶ with its end adapted to contact with the front of the frame D and has a check nut f⁷ adapted to lock it from turning. By loosening the screw f² and nut f⁷ and turning the screw f⁵ the plate f can be adjusted outward or inward on the frame D to a slight extent. The object of this adjustment is to regulate the position of the operating element of the ratchet-mechanism for the device which is moved through contact with a pin c⁸ on the traverse-bar C as hereinafter more fully explained.

The controller-arm E is mounted on a stud H pivoted in a bearing in a lug f⁸ extending from the front of the plate f. The stud H has a portion of its length squared off at h to fit a square hole e' in the arm E, see Fig. 8, and above the squared portion the stud is turned down and threaded at h' to receive a nut h²; see Figs. 4 and 9. The middle portion h³ of the stud H is fitted to turn in its bearing in the lug f⁸ and is formed with a flange h⁴ abutting the under side of the lug, as shown in Fig. 4. After the arm E is seated on the squared portion h of the stud a washer h⁵ is placed on the threaded end h' and set up against the arm by screwing down the nut h². This serves to bind the arm E against the shoulder h⁶ and the stud is held from longitudinal movement in its bearing by the arm E abutting one side of the lug f⁸ while the flange h⁴ abuts the other. The lower, butt end h' of the stud H is formed with a cross-cut h⁸ which can be used as a slot for the screw-driver and also serves to hold the end i of a coiled, wire spring I. The spring I is coiled around the end portion h' of the stud H with its upper end bent around to engage a groove or depression f⁹ in the side of the lug f⁸, see Figs. 3 and 4. The spring I is placed in position as above described under tension and its tendency is to turn the stud H and arm E in the direction indicated by the arrow x, Fig. 2.

To the inner end of the arm E is connect-

ed one end of a link J by means of a stud *j*. The opposite end of the link J is connected by a stud *j'* to the forward end of a pivoted member or arm K, see Figs. 3, 4 and 5. The member K is pivoted at its rear end on the end of a slide member L by means of a stud *k*. The slide L is fitted to guideways *f*¹⁰ and *f*¹¹ bent up from portions of metal cut away from the plate *f*, see particularly Figs. 5 and 6. Referring to the same views, the rear end of the slide L is bent around in a loop *l* having an upper portion *l'* overlapping the top of the member K. The stud *k* has an enlarged portion *k'* pivoted in a bearing in the portion *l'* and its end is screwed into the member K with the shoulder *k*² tightened against the upper face of the latter. The outer end of the member K is bent downward at *k*³ and formed with an elongated, rectangular portion *k*⁴, see Figs. 4 and 5, having a longitudinal slot *k*⁵. The outer end of the slide L projects through the slot *k*⁵ and acts as a guide for the member K as the latter swings on its pivot *k*. Below the slide L the rectangular portion *k*⁴ of the member K is formed with a lug *k*⁶ which is bent forward at *k*⁷, see Fig. 5, to adapt its end to engage with the pin *c*³ which projects upwardly from the traverse-bar C.

Referring to Fig. 1, the pin *c*³ forms a part of the fastening means for the former-arm *g*³, before referred to, which is secured to the end of the bar C. By utilizing this pin to serve as a contact means between the bar C and member K I avoid adding extra parts to the main operating elements of the machine.

Referring now to Figs. 6 and 8, the slide L carries a pawl O adapted to engage the teeth of a ratchet-wheel M. The ratchet-wheel M operates in conjunction with a second, smaller ratchet-wheel N, arranged above it, to regulate the release of the arm E. Both ratchets M and N are mounted on a stud P and are connected to rotate together as now described: The stud P has a flat head *p* riveted against the plate *f* of the casing F, see Fig. 7. The wheels M and N are both fitted to rotate on the main portion *p'* of the stud P and are held in place by a flanged sleeve Q. The sleeve Q is set down against the shoulder *p*² of the stud P by means of the nut *p*³ screwed on to the end of the latter and its lower edge overlaps the face of the wheel N. A wire spring R is coiled around the sleeve Q with one end *r* engaging a hole *n* in the wheel N and the opposite end *r'* sprung into a hole *q* in the flange of the sleeve. The tendency of the spring R is normally to rotate the wheel N in the direction indicated by the arrow *z*, Fig. 6. The wheel M is connected with the wheel N by means of a finger *m* formed on its periphery and bent up and around, as shown in Fig. 7, to engage the teeth *n'* of

the wheel N. It will be observed that the wheel M has only a little more than half its perimeter formed with teeth *m'*, and it is also to be noted that the wheel N is constructed with a break in its periphery taking the form of a V-shaped cam-surface or gap *n*². By removing the two wheels M and N from the stud P the finger *m* can be set to engage different teeth on the wheel N to adjust the position of the gap *n*² with respect to the last tooth *m*² on the wheel M for a purpose later explained.

Pivoted on a stud *s* screwed into the plate *f* is a simitar-shaped lever S having an elbow portion *s'*, see Figs. 1 and 4, terminating in a pointed projection *s*² adapted to engage the teeth *n'* of the wheel N as shown most clearly in Fig. 6. The opposite end of the lever S is formed with an arcuate edge-portion *s*³ provided with a detent-shoulder *s*⁴ at the inner end thereof. The curved edge *s*³ is adapted to receive the correspondingly-shaped end *e*⁵ of the arm E. A relatively long, flat spring T is secured to the plate *f* at one end by a screw *t* and has its opposite end bearing against the lever S to maintain the extremity of the latter bearing against the periphery of the wheel N. Adjacent the opposite end of the lever S is a caliper-like member U pivoted on a stud *u*. The member U has its two divergent legs formed with rounded extremities *u'*, *u*², one of which *u'* bears against the rear edge of the lever S, while the other *u*² is adapted to be engaged by the rear end of the arm E.

Referring to Figs. 5 and 6, the pawl O is mounted on a pin or stud *o* adapted to turn in a bearing in the slide L. The pawl O is formed with a projection *o'* adapted to hook into the teeth *m'* of the ratchet M and is beveled off on opposite sides to provide a V-shaped point *o*² at its end. The point *o*² is adapted to enter a slot or opening *f*¹² formed in the guideway *f*¹¹ of the plate *f* to cause the pawl to be withdrawn from engagement with the ratchet teeth *m'*. A wire spring V is coiled around a screw *v* fastened in the plate *f* with one of its ends *v'* held against the upturned portion *f'* of the casing F. The opposite free end *v*² of the spring V is arranged to bear against the rear end of the pawl O and normally tends to swing the latter to carry its projection *o'* into engagement with the teeth *m'* of the ratchet M. The rear edge of the pawl O is slotted at *o*³ to provide a recess for the wire of the spring V and preferably the corner *o*⁴ is rounded off to allow the end *v*² of the spring to slide freely across it. The spring V besides acting to operate the pawl O also serves to move the slide L forward during the operation of the mechanism as later explained. Referring to Figs. 2 and 3, these illustrate the slide L in its forward

position, and it will be observed that the pointed end o^2 of the pawl is engaged by the slot f^{12} to hold the pawl away from the ratchet M. As the slide L is pressed backward in the direction indicated by the arrow 2, Fig. 2, the pointed end of the pawl is released from the slot f^{12} and the spring V will then act automatically to carry its projection o' into engagement with the teeth m' , see Fig. 6. The end v^2 of the spring V also serves as a stop by engaging the guideway f^{10} to limit the backward movement of the slide L; the forward movement of the slide being limited by the engagement of the end of the pawl O with the guideway f^{11} .

Referring to Fig. 8, I have here illustrated the arm E as adapted for adjustment to vary its length and thereby alter the position of the yarn-receiving slot e in relation to the butt of the bobbin b when the arm is in its operative position. As here shown the arm E consists of two sections E' and E² with the extension E² arranged 25 to slide on the main portion E'. A slot e^2 in the extension E² is adapted to receive a screw e^3 screwed into the section E', by which the parts are secured together, and a pin e^4 also fitted to the slot acts to maintain the parts in alignment.

Referring to Figs. 4 and 5, the mechanism of the device is protected from dust and lint by a cover W preferably formed of sheet-metal and bent to surround the 35 sides and ends of the casing F. The two sides w , w of the cover are formed with indented portions w' adapted to be sprung into slots f^{13} on the front and rear edges of the upturned ends f' , f' , and openings 40 w^2 , w^3 are left in the front and back for the slide L and member K which project beyond the edges of the plate f. A swelled-out dome w^4 covers the upwardly-projecting stud P and nut p^3 to give a neat and finished 45 appearance to the cover.

The operation of my complete device is as follows: The casing F is secured to the top of the frame D of the winding machine above the bearings for the spindle B and 50 traverse-bar C. This is accomplished by simply tapping a hole in the frame D for the screw f^2 at the proper location as shown in Fig. 1. The lug f^4 on the casing F is positioned to abut the edge of the frame D 55 at one end and the end of the adjusting screw f^5 engages the front of the frame at the opposite end. The screw f^5 is set to bring the casing F into such position that the pin c^3 on the traverse-bar C will strike 60 the end k^7 of the member K during the inward movement of the bar C to cause said member to move the slide L backward to the position illustrated in Fig. 6. In other words, the traverse of the bar C is slightly 65 longer than the distance between the pin c^3

and end of the member K as shown in Fig. 1, and hence the last end of the inward reciprocation of the bar will carry the member K and its connected slide L through a relatively slight extent of movement. Before starting to wind the bobbin the bobbin-receiver b is placed on the winding-spindle B and the yarn y is led up from its source of supply and its end secured to the receiver. The controller-arm E is next swung 70 toward the spindle B into the position illustrated by full lines in Fig. 1 and the yarn y is then led through the opening e at the end of the arm and threaded into the groove G' of the traverse-guide G. The arm E is moved manually to swing it into its operative position as shown in Fig. 1, and this acts to set the ratchet-mechanism of the device which operates automatically to release the arm after a predetermined number of 75 traverses of the yarn-guide. Referring to Figs. 2 and 3, when the arm E is swung from the position illustrated in the latter to that shown in the former it operates on the controlling-mechanism as follows: The inner curved end e^5 of the arm E first slides off from the end of the lever S and striking the end u^2 of the member U tilts the latter to cause its opposite end u' to rock the lever S against the action of its 80 spring T. This tilting action of the member U brings the end of the lever S forward beyond the end of the arm E and when the latter is released by the operator the parts will assume the position illustrated in Fig. 85 90 2. The lever S then acts as a detent for the arm E to prevent the latter from being moved under influence of the coiled spring I, see also Fig. 4. In the meantime the opposite end s^2 of the lever S will have been 95 raised free of the teeth on the ratchet N and this allows the spring R to rotate the ratchet in the direction indicated by the arrow z, Figs. 2, 3 and 6. The ratchet M being connected to the ratchet N through the finger 100 m^2 , the two wheels will rotate together until their turning movement is arrested by the finger m striking against the projection s^2 on the lever S. Coincident with the movement of the arm E the member K which is 105 connected thereto by the link J is carried from the position illustrated in Fig. 3 to that shown in Fig. 2, and, lying parallel with the slide L, its end k^7 will be in position to be engaged by the pin c^3 on the traverse-bar C. The bunch-building mechanism is now set to control the first winding on of the yarn and the machine is ready to be started; it being understood, of course, 110 that the manual operation of the arm E requires only an instant of time, much less, in fact, than that necessary for its explanation.

When the machine is started the spindle B will be rotated to wind the yarn on the 115 120 125 130

bobbin b and the guide G will be reciprocated longitudinally of the latter. Now, since at the beginning of the winding the yarn y leads to the bobbin through the opening e in the arm E the reciprocation of the guide will have practically no effect to traverse the yarn, but will simply draw it out in the free length y' , see Fig. 1, as the guide moves away from the arm. It will be noted that the slot e in the arm E is somewhat wider than the thickness of the yarn y and therefore the yarn will have a limited amount of play across the slot. This play of the yarn provides against the coils being laid on the bobbin one directly on top of another and results in giving a very slight width to the bunch-winding b' as illustrated in Fig. 1. Practically speaking, however, it can be said that the yarn is held from being traversed by the guide G during the bunch-winding. As before explained, it is only necessary to wind a comparatively few coils for the bunch-winding and after this is completed the arm E is released to allow it to swing into its inoperative position as illustrated by dotted lines in Fig. 1. The release of the arm E is effected as follows: Each time the traverse-bar C is reciprocated in the direction indicated by the arrow 2, Fig. 1, to carry the guide G toward the butt of the bobbin b , the pin c^3 on the bar will strike the end k' of the member K to move the slide L backward against the action of the spring V. Referring to Figs. 2 and 6, this movement of the slide L releases the end of the pawl O from the slot f^{12} and allows its projection o' to engage one of the teeth m' on the ratchet M. As the slide L continues its rearward movement to the position illustrated in Fig. 6, the pawl O will turn the wheel M through the space of one tooth. The turning of the wheel M effects a corresponding rotation of the ratchet N connected therewith and this movement takes place at the end of each stroke of the traverse-bar C. During this intermittent rotation of the ratchets M and N the projection s^2 at the end of the lever S rides over the teeth n' and by engagement with the latter prevents the two ratchets from rotating backward under the influence of the spring R. As the wheel N is turned by the pawl O in the direction opposite to that indicated by the arrow z , the gap n^2 in its periphery gradually approaches the projection s^2 on the lever S until it finally reaches the position illustrated in Fig. 3. At this point the projection s^2 will pass off from the last tooth n' and this allows the spring T acting on the edge of the lever S to tilt the latter into the position illustrated in Fig. 3. This movement of the lever S frees its end from the side of the arm E and allows the latter to be swung under influence of its spring I in the direction indicated by the arrow x .

The swinging movement of the arm E carries its outer end away from the bobbin b , see dotted lines in Fig. 1, while its inner end rides on the curved edge s^3 of the lever S until it strikes the detent shoulder s^4 . As the end of the arm E swings away from the bobbin b the yarn y is released from the opening e and henceforth the movement of the yarn is unrestricted so that the guide G will traverse it on the bobbin to build up the layers of the service-winding which constitute the main body of the bobbin. The swinging movement of the arm E besides acting to release the yarn y also serves to remove the member K from further contact with the pin c^3 . As the arm E moves to the position shown in Fig. 3 the link J carries the member K to the left and moves the lug k^6 out of range of the pin so that there can be no further engagement between the two. This prevents further action of the ratchet-devices and therefore all the parts remain in their inoperative positions until the completion of the bobbin when they are set again by the operator, as previously described. As before stated the device can be set to regulate the number of turns or coils in the bunch-winding and this is accomplished by adjusting the ratchet-mechanism in the following manner: The number of teeth m' engaged by the pawl O before the wheel N is turned into position to allow the end of the lever S to enter the gap n^2 determines the number of reciprocations of the traverse-bar required to effect the releasing of the arm E. As illustrated in Fig. 6, the device is adjusted with eight teeth intervening between the projection s^2 and the gap n^2 in the wheel N. Therefore it will require eight reciprocations of the slide L to turn the wheel N into the position illustrated in Fig. 3 to allow the detent-lever S to release the arm E. This means that eight reciprocations of the traverse-bar C take place while the yarn y is held from being traversed by the guide G and the number of turns in the bunch-winding b' thus formed depends upon the ratio of speed between the winding-spindle and traverse-bar. That is to say, the winding-spindle is generally driven at such a rate of speed that it makes several rotations to one complete reciprocation of the yarn-guide, the mechanism of the machine usually being adjustable to vary this ratio. Now, if the machine is set to give say, for example, ten turns of the spindle for each reciprocation of the yarn-guide, then there will be ten turns or coils of yarn wound on the bobbin during the movement of the wheel N through the space of one tooth. It will thus be seen that if the ratchet-mechanism is set as here illustrated, to release the arm E after eight teeth have passed under the end of the lever S, then during this time the winding-spindle will

have been rotated eight times ten or eighty turns and therefore there will be eighty coils wound into the bunch before the guide commences to traverse the yarn to build up the main or service-winding of the bobbin. By removing the wheels M and N from the stud P and changing the position of the finger m on the teeth n', the relation of the gap n² to the projection s² can be varied so as to provide for a greater or less number of reciprocations of the slide L before the release of the arm E. In this way the automatic operation of the device can be regulated to adapt the machine to wind different lengths of yarn in the preliminary winding or bunch as may be required for different classes of weaving.

In some cases, with different designs of feeler-looms, it is desirable to change the location of the bunch with respect to the butt of the bobbin; that is, to wind it a greater or less distance therefrom. This is accomplished by simply loosening the screw e³ illustrated in Fig. 8 and extending or shortening the length of the arm E so as to vary the position of the slot e in relation to the end of the bobbin.

It will be seen from the above that my invention provides an extremely simple and compact mechanism for effecting the bunch-winding in bobbins or cops and one which can be applied to any usual form of winding machine without change in the mechanism thereof. It can be attached to the machine practically without machining operations, merely requiring the tapping of a single hole, and will operate in conjunction with almost any form of traverse-mechanism without alteration or adjustment of the elements therein. It can be set to give any desired number of turns in the bunch-winding, to vary the yardage therein, and can be adjusted to regulate the position of the bunch on the bobbin.

Various modifications might be made in the form and arrangement of my new device without departing from the spirit or scope of the invention.

Therefore, without limiting myself to the exact construction shown and described, what I claim is:—

1. In a winding machine, the combination with the winding-spindle and traverse-guide adapted to be reciprocated with respect to each other to traverse the yarn on the spindle, of automatically-operated means adapted to engage the yarn to limit its extent of traverse at the commencement of the winding to effect the building of a bunch on the bobbin composed of coils wound with a relatively short traverse.

2. In a winding machine, the combination with the winding-spindle and traverse-guide adapted to be reciprocated with respect to each other to traverse the yarn on the spin-

dle, of means operating independently of said spindle and guide adapted to engage the yarn to withhold it from being traversed except to a slight extent at the beginning of the winding to effect the building of a bunch on the bobbin having the coils therein laid at a fixed point in relation to the butt of the bobbin.

3. In a winding machine, the combination with the winding-spindle and yarn guide adapted to be reciprocated with respect to each other to traverse the yarn on the spindle, of means to engage the yarn to limit its traverse at the beginning of the winding to effect the building of a bunch on the bobbin, and devices to operate said means to release the yarn at the completion of the bunch to allow it to be traversed to wind the main portion of the bobbin.

4. In a winding machine, the combination with the winding-spindle and yarn-guide adapted to be reciprocated with respect to each other to traverse the yarn on the spindle, of means to engage the yarn to limit its traverse during a predetermined number of rotations of the spindle to wind a bunch on the bobbin, and means to release said holding-means at the completion of the bunch to allow the yarn to be traversed to build the main portion of the bobbin.

5. In a winding machine, the combination with the winding-spindle, of means to traverse the yarn on said spindle, devices to engage the yarn to prevent it from being traversed by said means except to a slight extent at the beginning of the winding to build a bunch on the bobbin, and means to release the yarn from the controlling-devices at the completion of the bunch to allow it to be traversed to build the main portion of the bobbin.

6. In a winding machine, the combination with the rotating winding-spindle and reciprocating traverse-guide, of means to engage the yarn to hold it from being traversed to the full extent by the guide during a predetermined number of reciprocations of the latter to build a bunch on the bobbin, and automatically-operated means to release said yarn from the holding-means to permit of its being traversed by the guide to build the main portion of the bobbin.

7. In a self-contained attachment for winding machines, adapted to be applied thereto to operate in conjunction with the winding-spindle and traverse-guide thereof, the combination of means adapted to hold the yarn from being traversed to the full extent by the guide at the beginning of the winding to build a bunch on the bobbin, and automatically-operated means to release the yarn from the holding-means at the completion of the bunch to allow of its being traversed to wind the main portion of the bobbin.

8. In a winding machine, the combination with the winding-spindle and traverse-mechanism for traversing the yarn on the spindle, of means to hold the yarn from being traversed to the full extent at the beginning of the winding to build a bunch on the bobbin, and means operated from said traverse-mechanism to actuate the holding-means to release the yarn therefrom after a predetermined number of rotations of the winding-spindle.

9. In a winding machine, the combination with the winding-spindle and yarn-guide adapted to be reciprocated with respect to each other, of yarn-controlling means adapted to be thrown into position to engage the yarn as it leads to the bobbin to hold it from being traversed to the full extent on the spindle at the commencement of the winding, means to retain said yarn-controlling means in operative position during a predetermined number of rotations of the spindle, and means operated automatically to release the yarn from said means to allow it to be traversed on the spindle.

10. In a winding machine, the combination with the winding-spindle and yarn-guide adapted to be reciprocated with respect to each other, of a controller-arm adapted to be operated manually to bring it into position to engage the yarn leading from the guide to the bobbin to prevent the yarn from being traversed to the full extent on the spindle, means to maintain the arm in its operative position during a predetermined number of rotations of the spindle, and means to release the arm to allow it to return to its inoperative position to permit the yarn to be traversed.

11. In a winding machine, the combination with the winding-spindle and yarn-guide adapted to be reciprocated with respect to each other, of an arm adapted to be moved into position to engage the yarn leading from the guide to the spindle, means to retain the arm in its operative position, means operating automatically to release said retaining-means, and means to return the arm to its inoperative position after the release of the retaining-means.

12. In a winding machine, the combination with the winding-spindle, of a yarn-guide adapted to traverse the yarn on the spindle, means adapted to engage the yarn leading from the guide to the spindle to withhold it from being traversed to the full extent, means to retain the yarn-holding means in operative position, means to release the retaining-means to allow the yarn-holding means to return to its inoperative position, and means to adjust the releasing-means to regulate its time of action.

13. In a winding machine, the combination with the winding-spindle and yarn-guide adapted to be reciprocated with re-

spect to each other to traverse the yarn on the spindle, of a controller-arm adapted to engage the yarn leading from the guide to the spindle to prevent its traverse to the full extent and effect the building of a bunch on the bobbin, and means to adjust the length of the arm to regulate the position of the bunch on the bobbin.

14. In a winding machine, the combination with the winding-spindle, of a yarn-guide for traversing the yarn on the spindle, a controller-arm adapted to engage the yarn leading from the guide to the spindle to prevent its traverse to the full extent thereon, detent-means to hold said arm in its operative position, automatically-operated means to release said detent-means, and a spring to carry said arm into its inoperative position after the release of the detent-means.

15. In a winding machine, the combination with the winding-spindle, of a reciprocating yarn-guide for traversing the yarn on the spindle, a controller-arm adapted to be moved into position to engage the yarn leading from the guide to the spindle to prevent its traverse to the full extent thereon, detent-means to retain the arm in its operative position, a ratchet-mechanism for releasing said detent-means, and means operated from the reciprocation of the yarn-guide to actuate the ratchet-mechanism.

16. In a winding machine, the combination with the winding-spindle, of a reciprocating yarn-guide for traversing the yarn on the spindle, a controller-arm adapted to be moved into position to engage the yarn leading from the guide to the spindle to prevent its traverse to the full extent thereon, detent-means to retain the arm in its operative position, a ratchet-mechanism for releasing said detent-means, means operated from the reciprocation of the yarn-guide to actuate the ratchet-mechanism, and means to adjust the ratchet-mechanism to regulate the time of release of the detent-means.

17. In a winding machine, the combination with the winding-spindle and yarn-guide, of a traverse-bar for reciprocating the guide, an arm adapted to be moved into position to engage the yarn leading from the guide to the spindle to prevent it from being traversed to the full extent by the guide, detent-means to retain the arm in its operative position, a ratchet-mechanism for releasing said detent-means, a pawl for operating said ratchet-mechanism, a slide for operating the pawl, and means on the traverse-bar for moving the slide to actuate the pawl.

18. In a winding machine having a winding-spindle and traversing yarn-guide, the combination with the frame thereof, of a casing attachable thereto, a controller-arm mounted in said casing and arranged to be moved into position to engage the yarn lead-

- ing from the guide to the spindle to prevent its traverse to the full extent on the latter, 30 detent-means to retain the arm in its operative position, and means operated from the machine to release the detent-means after a predetermined number of rotations of the spindle to cause the controller-arm to return to its inoperative position and allow the 35 yarn to be traversed on the spindle.
19. In a winding machine, the combination with the winding-spindle and traverse-mechanism, of a controller-arm adapted to engage the yarn to prevent it from being traversed to the full extent on the 40 spindle, detent-means to retain said arm in its operative position, means to release the detent-means to disengage the arm from the yarn, means actuated from the traverse-mechanism to operate the releasing-means, 45 and means to render said last-named means inactive after the arm is released from the detent-means.
20. In a winding machine, the combination with the winding-spindle and traverse-mechanism, of a controller-arm adapted to engage the yarn to prevent it from being traversed to the full extent on the spindle, 50 detent-means to retain said arm in its operative position, and means actuated from the traverse-mechanism to release the detent-means, said means adapted to be carried out of operative relation to the traverse-mechanism upon the release of the controller-arm.
21. In a winding machine, the combination with the winding-spindle and traverse-mechanism, of a controller-arm adapted to engage the yarn to prevent its traverse to the full extent on the spindle, detent-means to retain the arm in its operative position, 55 means operated from the traverse-mechanism to actuate the detent-means to release the arm, and means to move said detent-actuating means out of range of the traverse-mechanism after the arm is released.
22. In a winding machine, the combination with the winding-spindle and traverse-mechanism, of a yarn-controlling means adapted to hold the yarn from being traversed to the full extent on the spindle, 60 detent-means to retain the yarn-controlling means in operative position, a ratchet to release the detent-means, a second ratchet connected to operate the first ratchet, means to actuate the second ratchet, and means to adjust the ratchets in relation to each other 65 to regulate the time of release of the detent-means.
23. In a bunch-building device for winding machines, the combination with controller-means adapted to be moved into position to engage the yarn, of detent-means to hold said controller-means in operative position, a ratchet-wheel for releasing said detent-means, a second ratchet-wheel connected to the first ratchet and adjustable 70
- rotatively in relation thereto, and means to turn the ratchets to release the detent-means.
24. In a bunch-building device for winding machines, the combination with an arm adapted to be moved into position to engage the yarn, of a detent-lever engaging said arm to maintain it in its operative position, a ratchet-wheel engaging said lever and having a cam-surface adapted to receive the end thereof, and means to turn the ratchet to allow the lever to enter the cam and release the arm. 75
25. In a bunch-building device for winding machines, the combination with an arm adapted to be moved into position to engage the yarn, a detent-lever arranged to engage the arm to hold it in its operative position, said lever formed with a projection at one end, a ratchet-wheel having teeth adapted to be engaged by the projection on the detent-lever and formed with a gap in its periphery, and means to turn the ratchet to allow the projection to enter the gap in the ratchet to cause the detent-lever to release 80 the arm. 85
26. In a bunch-building device for winding machines, the combination with an arm adapted to be moved into position to engage the yarn, of a detent-lever to maintain said arm in its operative position, a ratchet-mechanism to release said detent-lever from the arm, a slide, a pawl carried by said slide to operate the ratchet-mechanism, a member pivoted on the slide, reciprocating-means engaging the pivoted-member to actuate the slide, and means connecting the pivoted-member with the arm to cause the latter to act when released to carry said member out of range of the reciprocating-means. 90
27. In a bunch-building device for winding machines, the combination with an arm adapted to be set in position to engage the yarn, of a detent-lever to maintain the arm in its operative position, a spring to move the detent-lever to release the arm, means to hold the detent-lever against the action of the spring, and means to operate said holding-means to allow the detent-lever to be moved by its spring to release the arm. 95
28. In a bunch-building device for winding machines, the combination with an arm adapted to be set in position to engage the yarn, of a detent-lever to maintain the arm in its operative position, means to release said detent-lever from the arm, and means to cause the detent-lever to engage the arm again when the latter is carried into operative position. 100
29. In a bunch-building device for winding machines, the combination with an arm adapted to be moved into position manually to engage the yarn, of a detent-lever to maintain the arm in its operative position, a spring to move the detent-lever to release 105
- 110
- 115

it from the arm, means to hold the detent-lever against the action of the spring, devices to operate said holding-means to allow the arm to be moved by its spring, and a member engaging the detent-lever and adapted to be operated by the manual movement of the arm to cause the lever to engage the arm to retain it in operative position.

30. In a bunch-building device for winding machines, the combination with an arm adapted to be moved into position manually to engage the yarn, of a detent-lever to engage the arm, means to release the detent-lever from the arm, means to move the arm into inoperative position when released by the detent-lever, and means operated from the manual movement of the arm to move the detent-lever to engage the arm to retain the latter in operative position.

31. In a bunch-building device for winding machines, the combination with means adapted to engage the yarn, of detent-means for holding said means in operative position, a ratchet to operate said detent-means to release the yarn-engaging means, a reciprocating slide, a pawl carried by said slide, a spring for operating the pawl to cause it to engage the ratchet when the slide is reciprocated, and means engaging the pawl at one end of the stroke of the slide to release said pawl from the ratchet.

32. In a bunch-building device for winding machines, the combination with a yarn-engaging member, of a detent-lever formed with a projection at one end and adapted to engage the yarn-engaging member at its op-

posite end to maintain the latter in operative position, means to move the detent-lever to release the yarn-engaging member, a ratchet-wheel, having teeth engaged by the projection on the detent-lever and formed with a gap in its periphery, a second ratchet-wheel having a finger adapted to engage one of the teeth on the first wheel, a spring tending to rotate the wheels to bring the finger against the projection on the detent-lever, and means to rotate the wheels against the action of the spring to bring the gap in the ratchet in line with the projection on the detent-lever to allow the latter to be moved to release the 50 yarn-engaging means.

33. In a bunch-building device for winding machines, the combination with an arm adapted to engage the yarn, detent-means to retain the arm in its operative position, means to move the arm to disengage it from the yarn upon release of the detent-means, a ratchet engaging the detent-means to hold it in operative engagement with the arm, a spring tending to rotate the ratchet in one direction, means to limit the extent of rotation of the ratchet under influence of the spring, and means to rotate the ratchet intermittently against the action of the spring to cause it to release the detent-means.

In testimony whereof I affix my signature in presence of two witnesses.

WILLIAM MARCROFT.
